UNITED STATES PATENT OFFICE.

WILLIAM H. FULLINGTON, OF CLEVELAND, OHIO, ASSIGNOR TO KATHERINE J. RIDDELL, OF CLEVELAND, OHIO.

CRUTCH.

Application filed October 22, 1925, Serial No. 64,155. Renewed June 11, 1927.

This invention relates to new and useful improvements in surgical appliances and more especially in crutches.

One object is to provide a crutch adjustable to accommodate persons of varying stature.

Another object in a crutch is to provide improved cushioning and shock absorbing means.

10 Another object is to provide a crutch with means for adjusting the height of the arm saddle for accommodating persons of varying height.

Another object is to provide a hand grip adjustable in relation to the arm saddle to accommodate persons of varying arm lengths.

Another object is to provide shock absorbing means for resiliently mounting an arm saddle.

20 Another object is to provide a crutch with an interchangeable arm saddle.

Another object is to provide an improved padded arm saddle for comfort.

Another object is to provide an interchangeable sanitary impadded arm saddle for regular usage over long periods.

Another object is to provide an improved crutch base tip.

Another object in a base tip is to provide 30 improved means for detachably mounting the cushion.

Another object is to provide an improved detachable base tip cushion with a pointed member adjustable to protrude through for engagement with the ground when slippery or covered with ice.

Another object in a detachable crutch cushion is to provide an adjustable pointed member having an elongated shank adapted 40 to be applied as a lever for loosening or tightening the crutch adjusting means.

In the drawings:—

Figure 1 is a view showing the crutch equipped with an improved padded arm saddle and extension means;

45 Figure 2 is an enlarged sectional view with parts broken away;

Figure 3 is an enlarged section taken on line 3—3 of Figure 1, showing the hand grip;

50 Figure 4 is an enlarged sectional detail of the base tip;

Figure 5 is a detail view of the cushion;

Figure 6 is a fragmentary sectional view

showing the base tip modified for application to a standard length crutch;

Figure 7 is another modified form of base tip application to an ordinary split rod crutch; and

Figure 8 shows an ordinary unpadded arm saddle interchangeably applied to the crutch.

In the drawings 1 indicates generally the improved crutch shown in Figure 1, comprising a main tube or shaft 2 of steel or other suitable material which forms the main support of the crutch. The saddle generally indicated by the numeral 3 is resiliently mounted in the top of the tube 2 by a depending extension 4 resting on resilient member 5 supported by plug 6 pinned to the tube 2 as at 7. The sliding movement of extension 4 is limited by a screw 8 threaded into the tube 2, said screw engaging the ends of slots 9 in the annular wall of extension 4 which is hollow to lighten the structure. Extension 4 depends centrally from a yoke 10, the arms 11 of which extend oppositely and upwardly, terminating in somewhat reduced flattened portions 12. Flattened portions 12 are provided with bolt holes 13 to receive bolt 14. Arm saddle 15 is approximately round in cross section and is preferably formed of a leather casing 16 stitched or otherwise joined on the underside and reenforced and stuffed with raw hide or other suitable material, near the ends 17 of saddle 15 the stuffing is reduced and the casing and reenforcing is flattened, bent down and under yoke end portions 12 and clamped by bolts 14 extending thru from the top and tightened by nuts on underside. Some people who have worn crutches do not care for the padded arm saddle, and in that case the unpadded wooden saddle 20 as shown in Figure 8 may be substituted and this form is supported on the annular shoulder 22 and stud 23 of a post 21. Saddle 20 is partly drilled on under side to receive stud 23 which is secured by pin 24. Post 21 is adapted to slidingly fit into the top of tube 2 and rest on resilient member 5. Movement of post 21 is limited by the screw 8 engaging the ends of slot 25, preventing displacement.

An adjustable hand grip is provided comprising a split sleeve 26 integrally formed with arms 27 extending oppositely and then turning outwardly, terminating with ends

provided with holes to receive a bolt 28. Intermediately supported on bolt 28 between arm ends 27 is a hand grip 29, and this hand grip is adjustable in relation to the arm 5 saddle accommodating the arm reach of the crutch user, by sliding sleeve 26 up or down on tube 2 and clamping same thereon by drawing up nut 30 on bolt 28, springing arms 27 together and compressing sleeve 26 10 on tube 2 and also binding the arm ends 15 against grip 29 preventing turning of the latter.

An adjustable extension 31 provides height adjustment of saddle and comprises 15 a tube 31 slidably fitting into lower end of main tube 2 which is externally threaded as at 32 at its lower end to receive knurled nut 33 internally taper-threaded. When nut 33 is turned up by hand or with a spanner 20 wrench engaging in hole 36, the tapered thread compresses tube portion 32 into frictional locking engagement with extension tube 31. To permit sufficient compression 25 of tube end 32 one or more slots are cut longitudinally back from the end a distance somewhat greater than the thread.

A crutch base tip indicated generally at 35 is mounted on the end of extension 31. As shown in Figure 2 base tip 35 is recessed 30 at 37 forming a socket to receive the lower end of extension tube 31 which is fitted internally with a ring 38 pinned to tube 31 as at 39. Base tip 35 is drilled centrally as at 36 and extending into the upper portion of the hole is a tube 40 of small diameter pinned as at 41 to the base 35. Tube 40 extends thru ring 38 and is provided with a collar 42 pinned at 43 to the tube 40, said collar 42 retains the lower end of tube 31 in socket 45. The annular flange of socket 37 covers pin 39 preventing displacement upon working loose. Tube 40 extends upwardly and centrally thru extension tube 31, terminating with a threaded end to draw or push 50 tapered nut 45 extending partly into the upper split end of extension tube 31. Upon rotation of base tip 35 carrying tube 40, tapered nut 45 is drawn into the split tube end 46 expanding and frictionally locking the latter against tube 2. This means for locking extension 31 may be employed together with the locking means provided at lower end of tube 2, or may be omitted when employing the latter means, in which case 55 the lower end of extension tube 31 is secured directly to socket 37.

Base tip 35 is provided with a shock absorbing cushion 47 removably secured in a lower socket 48 having an internal annular shoulder 49 for supporting the base on 60 said cushion which projects below socket 48 for supporting cushioning engagement

with the ground. Socket 48 is provided at its lower internal edge with an inwardly extending annular bead 50 for gripping and 65 slightly compressing rubber cushion 47, preventing displacement or falling out. The rubber cushion may be easily inserted or removed from socket 48 with the hand.

A pointed screw 51 is screwed centrally 70 into the top of cushion 47 and locked with lock nut 54. The shank 52 of screw 51 is plain and at the end may be slotted as at 53 for turning. During inclement weather 75 when the ground is slippery or covered with ice, a positive grip with the ground may be obtained by screwing down screw 51 until the point projects slightly beyond the bottom of cushion 47 as shown in Figure 4. The shank 52 extends upwardly into the somewhat larger hole 36 in base 35. Shank 80 52 is adapted to be used as a lever for turning base 35, by removing cushion 47 and inserting shank 52 into transverse hole 55 in base 35.

Some people prefer a crutch of standard length without the feature of saddle height adjustment to the ground and for this purpose the form shown in Figure 6 is provided in which the main tube 54 is cut to a predetermined length and the base tip 55 is applied directly to the end as shown in Figure 6. In this form the base is turned down to a shoulder 56 for butting engagement with the end of tube 54 the turned down portion 57 fitting into tube 54 with a tight fit and pinned at 58.

Another modified form of application of the base tip is shown in Figure 7 in which a deep socket 61 formed in the upper portion of base 60 is adapted to receive the end 62 of a standard wooden crutch. A pin 63 secures the crutch end securely to the base.

I claim:—

1. A crutch shaft comprising upper and lower telescopic tubes, the upper end of the lower tube being expansible into contact with the inside of the upper tube, a rotary socket block on the lower end of the lower tube, said socket block being provided with a tread piece, a screw rod fixed at its lower end to said socket block and extending upwardly therefrom into the inner tube, and means actuated by said screw rod to expand the upper end of the inner tube.

2. A crutch shaft as stated in claim 1, the lower end of the inner tube being provided with an internal bearing in which the screw rod may turn, and a collar on the rod above said bearing, to hold the socket block in position on the inner tube.

In testimony whereof, I affix my signature.

WILLIAM H. FULLINGTON.
